(57) **CLAIM**

I claim, the ornamental design for the toilet splatter shield, as shown and described.

DESCRIPTION

FIG. 1 is a front elevational view of the toilet splatter shield showing my new design;

FIG. 2 is a rear elevational view of the toilet splatter shield thereof;

FIG. 3 is a left-side elevational view of the toilet splatter shield thereof;

FIG. 4 is a top plan view of the toilet splatter shield thereof;

FIG. 5 is a bottom plan view of the toilet splatter shield thereof; and,

FIG. 6 is a perspective view of the toilet splatter shield thereof.

The broken line showing a toilet is for illustrative purposes only and forms no part of the claimed design.
